UNITED STATES PATENT OFFICE.

JOHN H. ROBINSON, OF WASHINGTON, DISTRICT OF COLUMBIA.

TARIFF-CHART.

1,029,085.

Specification of Letters Patent. Patented June 11, 1912.

Application filed April 29, 1912. Serial No. 693,903.

To all whom it may concern:

Be it known that I, JOHN H. ROBINSON, a citizen of the United States, residing at Washington, in the District of Columbia, 5 have invented certain new and useful Improvements in Tariff-Charts; and I do hereby declare the following to be a full, clear, and exact description of the same, reference being had to the accompanying drawings, 10 forming part of this specification, and to the figures and letters of reference marked thereon.

The present invention relates to a chart for assisting in the determination of charges 15 for the transportation or carriage of goods from any point to any other point within a given geographical area. The chart is based upon what is known as the "zone principle" in which each point of origin is presumed to 20 be at the center of a surrounding series of zones and the charges for transportation from said point of origin or center to all points in a zone are the same, the rates, of course, depending upon the distance of the 25 zone from the point of origin.

One of the objects of the invention is to provide a chart which may be readily adapted for use in determining the charge to be made from any point of origin within the 30 geographical area to any other point or points of destination within said area, whereby the cost of producing the charts may be greatly reduced, and an absolute uniformity in the charges secured without 35 the necessity of but occasionally consulting the rate schedules such as are now in common use or the rate guide which is designed to be published in connection with the chart to serve as a check or guide for conditions 40 and situations not clearly indicated by the chart, or for which the chart may serve as a key to facilitate the location of the desired information in the guide.

Other objects of the invention will appear 45 from the following description and claims.

Referring to the accompanying drawings,—Figures 1, 1^a, 1^b, and 1^c represent a chart of the geographical area of the United States of America divided into four parts 50 for convenience of illustration and to represent the area on a larger scale than would be possible on a single sheet of drawing; Fig. 2 is a representation of a chart more or less diagrammatic in character and on a very 55 much smaller scale than the representation in Figs. 1 to 1^c, inclusive, but showing the

zone boundaries substantially complete, in order that their relation to the geographical area represented may be more readily understood.

The chart adopted for illustrating the present invention is a conventionalized representation of the geographical area of the United States of America, and said area is represented as sub-divided throughout into 65 small rectangular areas all of uniform corresponding dimensions, each sub-division being the smallest desired unit area and the geographical distances between the corresponding boundaries of the areas being 70 supposed to be the same geographical distance throughout.

In order that the actual geographical boundaries may all fall within the rectangular unit areas, the geographical boundaries 75 are preferably conventionalized and represented as conforming to unit boundaries, the entire area therefore presenting the appearance of a conventionalized map, the boundary lines of which are formed entirely by 80 straight lines parallel and perpendicular to each other and parallel with the lines of sub-division within the area.

Referring particularly to Figs. 1 to 1^c it will be seen that the boundary lines of the 85 unit areas as well as of the geographical area are formed by vertical lines A, A, etc., and horizontal lines B, B, etc., preferably spaced uniformly and equally in both directions so as to sub-divide the map representation into 90 squares, the total number of which, in the chart illustrated, is 3544. Each square represents a unit area, and while it may be of any dimensions desired, preferably and for convenience, each rectangle is in its vertical 95 and horizontal dimension approximately thirty minutes of longitude and latitude, respectively, and each unit rectangle is identified by a number. For convenience in the ready location of any particular unit 100 rectangle or area, the vertical columns are numbered in multiples of fifty; that is to say, starting, for instance, at the upper left hand corner of the chart, the unit areas in the first vertical column, if represented, would be numbered from 0 to 49, inclusive; in the second vertical column from 50 to 99, in the third vertical column from 100 to 149, and so on, throughout the whole geographical area represented by the chart, the corresponding numbers in each series extending 105 in horizontal rows across the chart, and if a

unit area or rectangle be omitted in any vertical column the number for that unit or rectangle is also omitted. With this arrangement it becomes a simple matter to locate almost instantly a unit area the number of which is known. For example, to locate the unit area numbered 2925 the column headed by the number 2900 can be readily found at the top of the chart and following 10 down that column we find the desired number at once, whereby a postmaster or person desiring to figure a charge for transporting a package, having located from his guide the number of the unit area in which the point 15 of destination is located, turns to the chart and finding the unit area on the chart he can tell at a glance within which zone it lies, and can determine the charge accordingly.

With a chart as thus constructed, zone 20 areas or indications may be developed around any one of the unit areas as a center, each of which zones will have its boundary throughout substantially equidistant from the unit area forming the center, and 25 the zone boundaries by being made to conform in outline to the unit boundaries will constitute definite lines of demarcation between the zones, leaving no room for doubt or dispute as to the charge to be made for 30 transportation to a point in any one of the unit areas.

The zone boundaries in Figs. 1 to 1^c are defined by the distinctive marks F, which in the actual charts may be colored, and 35 the several zones are numbered from the center unit area outwardly with the large distinctive numbers 2, 3, 4, 5, etc.

In the specific scheme illustrated by the chart in the drawings the eight unit areas 40 grouped about another unit area are presumed to constitute the area in which the minimum charge is made, and this, in Fig. 1^c, is represented by the shaded area G, while the boundaries of the successively 45 larger zones are indicated by the distinctive lines F before referred to.

The area in which the minimum charge 50 pertains is in this specific embodiment the area of the unit in which the office of origin is located and the immediately adjoining units, for example, the eight surrounding units. By this arrangement the charges between proximate offices is always uniform, even though the offices of origin and destination be located in different proximate units.

Having once prepared the outlines of the 60 desired zones, it becomes a simple matter to impress those outlines upon the chart with any desired unit area as the center, and consequently the large number of charts which would be required for a parcels post system, for instance, can be prepared with the exception of the zone out- 65 lines, and the zone outlines be impressed

thereon at slight expense for each of the unit areas, or if so desired, a transparent or slip sheet having the zone outlines thereon may be placed over the chart with the center coinciding with the desired unit area, 70 whereby each postoffice within the unit area and each of the unit areas may be cheaply supplied with a chart from which the rate of charges may be quickly and accurately determined.

As a material factor in assisting a user of the chart to determine quickly from addressed packages the zone in which the point of destination is located, the chart should have indications of the political 80 boundaries within the geographical area, for it is customary in addressing packages or goods to be transported, to indicate the point of destination by the name of the postoffice and the political division or State 85 in which it is located. Inasmuch as confusion would necessarily arise should the true geographical boundaries of the political divisions be followed on the chart, said political divisions are conventionalized and 90 their boundary lines made to conform to or extend parallel with the boundary lines of the unit areas; for example, where the boundaries of the unit areas correspond to the boundary lines of the State, they will, of 95 course, coincide as at B' in Fig. 1^c, but where the boundary lines of the State meander, or cross a unit area and postoffices or points of destination are located within the area in both States, the boundary line of the 100 State is extended in right lines into or across the unit area as at B² in Fig. 1^c, thereby indicating to the user of the chart at a glance that the point of destination may be within one or the other of the zones, but in 105 the great majority of instances it will be found that the entire State is located within one or the other of the zones, and the charge for transportation may be told without a second thought. Should there be a 110 doubt, the guide in which all postoffices within a unit are given a number corresponding to that unit is consulted, and the number of the unit having been determined from the guide, a glance at the chart will 115 show within which particular zone it is located.

In Fig. 2 there is represented on a small scale the chart shown in Figs. 1 to 1^c and with the zone boundaries shown complete 120 or as complete as is necessary for an understanding of the invention. In this representation of the chart, the center unit for the zone areas is presumed to be the unit area No. 2925 shown in Fig. 1^a with the appropriate number thereon, but the unit areas of the chart shown in Fig. 2 are on 125 too small a scale to permit of being numbered.

Having thus described my invention what 130

I claim as new and desire to secure by Letters Patent of the United States, is:

1. A chart for aiding in the determination of charges for transportation of merchandise, etc., in any direction in a given geographical area, said chart having the geographical area represented as sub-divided throughout into small rectangular areas all of uniform corresponding dimensions and each representing the smallest desired unit of geographical area and a plurality of zone indications around one of said unit areas as a center, the boundaries of each of said zones coinciding with unit area boundaries, whereby the geographical distance of each zone boundary from the center unit may be made substantially uniform throughout. 55
2. A chart for aiding in the determination of charges for transportation of merchandise, etc., in any direction in a given geographical area, said chart having the geographical area represented as sub-divided throughout into small rectangular areas all of uniform corresponding dimensions and each representing the smallest desired unit of geographical area, there being distinctive boundary undulations for the political divisions extending only parallel with the unit boundaries, and a plurality of zone indications around one of said unit areas as a center, the boundary of each of said zones coinciding with unit area boundaries, whereby the geographical distance of each zone boundary from the center unit may be made substantially uniform throughout. 60
3. A chart for aiding in the determination of charges for the transportation of merchandise, etc., in any direction in a given geographical area, said chart having the geographical area defined by a conventionalized representation of the area with its boundaries formed only by straight horizontal and vertical lines and with the area so bounded, sub-divided into rectangular unit areas all of uniform corresponding dimensions. 65
4. A chart for aiding in the determination of charges for the transportation of merchandise, etc., in any direction in a given geographical area, said chart having the geographical area defined by a conventionalized representation of the area with its boundaries formed only by horizontal and vertical lines and with the area so bounded 70
- sub-divided into rectangular unit areas all of uniform corresponding dimensions, and a plurality of distinctive zone boundary indicating lines around one of said unit areas as a center, the boundary of each of said zones coinciding with unit area boundaries, whereby the geographical distance of each zone boundary from the center unit may be made substantially uniform throughout. 75
5. A chart for aiding in the determination of charges for the transportation of merchandise, etc., in any direction in a given geographical area containing political divisions, said chart having the geographical area defined by a conventionalized representation of the area with its boundaries formed only by straight lines normal to each other and with the area so bounded sub-divided into small rectangular unit areas all of uniform corresponding dimensions, there being distinctive lines representing the political divisions of the area, said distinctive lines extending only parallel with the boundaries of the unit areas and a plurality of distinctive zone boundary indicating lines around one of said unit areas as a center, the boundary of each of said zones coinciding with unit area boundaries, whereby the geographical distance of each zone boundary from the center unit may be made substantially uniform throughout. 80
6. A chart for aiding in the determination of charges for transportation of merchandise, etc., in any direction in a given geographical area, embodying a chart sheet having the geographical area represented as sub-divided throughout into small rectangular areas all of uniform corresponding dimensions and each representing the smallest desired unit of geographical area and a relatively movable zone sheet having a plurality of zone indications thereon, the boundary lines of each zone corresponding to unit boundaries, said sheets being adapted to be superposed to present a composite chart whereby any unit may constitute the zone center and the geographical distance of each zone boundary from said center may be made substantially uniform throughout and to coincide with unit boundaries. 85
